US0D1073318S

(12) **United States Design Patent** (10) **Patent No.:** **US D1,073,318 S**
(45) **Date of Patent:** **** May 6, 2025**

(54) **BASE FOR STORAGE BOX**

(71) Applicant: **L&F PLASTICS, CO., LTD.**, Miaoli County (TW)

(72) Inventor: **Mu-Chuan Hsu**, Miaoli County (TW)

(73) Assignee: **L&F PLASTICS, CO., LTD.**, Miaoli County (TW)

(**) Term: **15 Years**

(21) Appl. No.: **29/862,655**

(22) Filed: **Dec. 12, 2022**

(30) **Foreign Application Priority Data**

Jun. 23, 2022 (TW) 111303091

(57) **CLAIM**

The ornamental design for a base for storage box, as shown and described.

DESCRIPTION

FIG. 1 is a top front perspective view of a base for storage box showing my new design;

FIG. 2 is a front view thereof and the rear view being a mirror image;

FIG. 3 is a right side view thereof and the left side view being a mirror image;

FIG. 4 is a top view thereof;

FIG. 5 is a bottom view thereof; and,

FIG. 6 is a bottom rear perspective view thereof.

The dashed broken lines in the figures show portions of the base for storage box that form no part of the claimed design.

1 Claim, 5 Drawing Sheets
